UNITED STATES PATENT OFFICE.

FRANK A. ASSMANN, JR., OF CHICAGO, ILLINOIS, ASSIGNOR TO CONTINENTAL CAN COMPANY, OF SYRACUSE, NEW YORK, A CORPORATION OF NEW YORK.

STRIP-SEALED CONTAINER.

Application filed April 16, 1920. Serial No. 374,447.

To all whom it may concern:

Be it known that I, FRANK A. ASSMANN, Jr., a citizen of the United States, residing at Chicago, in the county of Cook, State of Illinois, have invented certain new and useful Improvements in Strip-Sealed Containers, of which the following is a description, reference being had to the accompanying drawing, and to the figures of reference 10 marked thereon.

The invention relates to new and useful improvements in containers, and more particularly to a container wherein one of the ends thereof is secured to the body portion 15 of the container by means of a detachable sealing strip.

An object of the invention is to provide a container of the above character wherein the sealing strip may be tightly drawn about 20 the flanges on the container body and the container end for sealing the container.

In the drawings:—

Figure 1 is a sectional view through a portion of the container having my im- 25 proved sealing strip applied thereto;

Fig. 2 is an end view of the same; and

Fig. 3 is a diagrammatic view showing the parts assembled for sealing.

The invention is directed broadly to a 30 container preferably formed of metal which includes a cylindrical body portion and a closure for each end thereof. One of the container ends is secured to the body portion by a detachable retaining strip, while 35 the other container end is secured to the body portion by double seaming. The retaining strip is preferably applied at the factory by the manufacturer of the container, and after the container has been 40 filled, then the other end is applied and joined by a double seam to the container body by the packer.

The container body is provided with a 45 horizontally extending flange and the container end which is secured thereto by the detachable retaining strip, also has a flange which is formed with an open curl or false wire at its outer edge. The sealing strip extends underneath the flange on the body 50 portion of the container and about the outer surface of the curled edge of the container end and terminates short of the flange on the container end.

Referring more in detail to the drawings, 55 I have shown my improvement supplied to

a container consisting of a body portion 1, one end of which is closed by a container end 2 which is rolled into a double seam with a flange on the body portion 1 as indicated at 3. The other end of the container 60 is closed by a container end 4, and this container end is secured to the body portion by a detachable retaining strip 5. As above noted, the end 4 is first attached to the container body, and this is done by the manufacturer of the container. After the container is filled, then the end 2 is applied and secured to the body portion by a double seam 3, and this is done by the packer. The body portion 1 is provided with a horizontally extending flange 6. The container 65 end 4 is provided with an inner recess forming a vertical wall 7 which engages within the body portion of the container. At the upper edge of the wall 7 is a horizontally 70 extending flange 8 which is rolled into a curl or false wire 9. This may be closed or slightly open. When said curled portion 9 is slightly open it forms an elastic curled portion which yields slightly when the sealing 75 ring is applied and the elasticity of this curled portion aids in holding the parts in tight sealed contact. Between the flange 6 and the flange 8, a suitable packing 10 may be placed. The retaining strip is provided with a horizontal section 11 and a vertical section 12. The parts are assembled as shown in Fig. 3, 80 after which the vertical section 12 is rolled about the curl 9 to the position shown in Fig. 1. At this extreme curled position, the 85 free edge 13 of the sealing strip is some distance from the upper face of the flange 8 so that any variation of thickness in the metal may be readily taken care of by rolling the vertical part 12 to a greater 90 or less extent about the curled portion 9 of the container end. This sealing ring 12 is split as indicated at 14, and at one end of the strip there is a projecting finger 15 which overlaps the other end of the strip. 95 This finger serves as a means for readily lifting the upper portion of the strip and the removal of the strip so as to release the container end 4. The rolling of the strip about the curled surface 9 enables the two 100 flanges to be very firmly gripped together and the limiting of the end 13 so that it does not contact with the surface of the flange 8 insures, as above noted, that said vertical portion 12 of the retaining strip 105 110

may be rolled a sufficient distance to bring about a tight joint. Instead of rolling the vertical wall 12 about this curled edge of the container end, from certain aspects of 5 the invention the sealing ring may be formed with the curled section, then applied to the container end, and the part 11 of the retaining ring rolled underneath the flange 6. In either instance, the drawing of the 10 retaining ring around the curved surface is what insures a tight joint being formed.

It is obvious that other forms of packing 15 may be used for sealing the joint, and that in place of a packing ring a sealing material may be placed either on the flange of the 20 container body or the flange of the container end, or, if desired, the sealing material may be placed on the sealing strip itself.

25 It is also obvious that minor changes in the details of construction and the arrangement of the parts may be made without departing from the spirit of the invention, as set forth in the appended claim.

Having thus described the invention, what I claim as new and desire to secure 30 by Letters Patent, is:—

A container comprising a body portion having a flange extending outwardly therefrom, a container end for closing one end

of the body portion, said container end having a flange parallel with the flange on the body portion, the outer edge of said flange on the container end being rolled in a curl, the upper surface of which is continuously 35 curved from the outer portion thereof to the extreme inner portion thereof, and a split metal sealing strip adapted to engage the under surface of the flange on the container body, to extend across the edge of the flange on said container body and about the curled curved edge of the container end, the inner edge of said sealing strip being curved to conform to the curled edge of the 40 container end and terminating short of the outer surface of the flange on the container end, whereby the drawing of the sealing strip about the curved surface of the curled edge of the container end will draw the container end into tight sealing contact with the can body, the inner edge of the curled portion of the container end terminating short of the flange on the end, whereby a hollow curl is formed giving an elasticity to the curled edge which aids in holding the parts in sealed contact when the sealing ring is drawn about the same.

In testimony whereof, I affix my signature.

FRANK A. ASSMANN, JR.
